UNITED STATES PATENT OFFICE.

MELVIN J. FOYER, OF CHICAGO, ILLINOIS, ASSIGNOR, BY MESNE ASSIGNMENTS, TO BOSTEDO PNEUMATIC TUBE COMPANY, OF CHICAGO, ILLINOIS, A CORPORATION OF ILLINOIS.

PNEUMATIC CONVEYER.

SPECIFICATION forming part of Letters Patent No. 750,356, dated January 26, 1904.

Application filed June 6, 1900. Serial No. 19,215. (No model.)

To all whom it may concern:

Be it known that I, MELVIN J. FOYER, of Chicago, in the county of Cook and State of Illinois, have invented certain new and useful Improvements in Pneumatic Conveyers; and I do hereby declare that the following is a full, clear, and exact description thereof, reference being had to the accompanying drawings, and to the letters of reference marked thereon, which form a part of this specification.

My invention relates particularly to an improvement in pneumatic conveying apparatus for use in stores or similar places for conveying cash-carriers to and fro between a central cashier's desk and outlying salesmen's stations. The apparatus may be used, however, for conveying parcels of any description and in any location within the limits of practicability.

My object is to provide apparatus of this character which can be more cheaply operated than any heretofore known, the time of the operator and character of the service being taken into consideration.

The accompanying drawings illustrate one practical embodiment of the several features of my invention, embracing a series of outgoing or distributing tubes which lead to the several salesmen's stations connected with a given cashier's desk and but one return or collecting tube leading to the cashier's desk. The distributing-tube for the farthest outlying station is in circuit with the collecting-tube. The distributing-tubes connect with the high-pressure or plenum side of a pressure-supplying mechanism—such as an air-compressor or, preferably, a rotary blower—and the collecting-pipe with the low-pressure or vacuum side thereof. Certain valves are supplied for momentarily admitting atmospheric pressure to the collecting-tube to convey carriers from the outlying stations, and other valves are supplied for admitting compressed air to the distributing-tubes. These valves are provided with time-regulators for controlling their closing movements, the pressure being admitted only sufficiently long to move the carrier quickly to its destination. It thus appears

that in the preferred form of the apparatus illustrated the collecting-tube is normally under suction adjacent to its delivery end, while the distributing-tubes are normally supplied with pressure adjacent to their despatching ends. This enables the cashier to use compressed air to send the carriers out, while it enables the several salesmen to use atmospheric pressure to send the carriers to the cashier.

In the said drawings, which illustrate my invention in its preferred embodiment, Figure 1 is a view diagrammatic in its nature, showing a central or cashier's station and several outlying or salesmen's stations and the manner of connecting the tubes; Fig. 2, a detail of a valve and a time-regulator therefor for use at an intermediate salesman's station; Fig. 3, a detail of the valve employed where a closed delivery end is desired; Fig. 4, a detail of the valve employed between the charging or despatching end of a distributing-tube and the point of admission of compressed air to said tube; Fig. 5, a detail of a gate-valve employed in connection with the distributing-tubes for preventing escape of compressed air except when propelling carriers, and Fig. 6 a plan section on line 6 6 of Fig. 5.

A represents a rotary blower, the blast or high-pressure side of which communicates with a compressed-air pipe B and the suction or low-pressure side of which communicates with a low-pressure pipe C. Where the type of blower shown is employed, a check-valve *a* may be used, if desired. The blower shown may be replaced, however, by any other type of blower, such as the well-known double-head positive rotary blower, which is of such construction as to prevent a backward flow of air when the machine is held at a standstill.

D E F represent a series of distributing-tubes having their charging ends supplied with doors D' E' F', controlled in closing by time-regulators D² E² F². Valve-casings D³ E³ F³ are interposed in the course of their respective tubes, and these are joined at their upper or outer portions by supply-pipes D⁴ E⁴ F⁴ with the compressed-air pipe B and at their lower

portions by exhaust or suction pipes $D^5 E^5 F^5$ with the low-pressure pipe C. The pipes $D^4 E^4 F^4$ are provided with gate-valves $D^6 E^6 F^6$, connected with the regulators $D^2 E^2 F^2$.

5 G represents an incoming collecting-tube, along the course of which are located salesmen's stations $H H' H^2$. It will be understood that the collecting-tube is shown disproportionately short. At these stations the tube G 10 is supplied with doors I I' I², connected with time-regulators J J' J². At the station H² the door I² serves also as a time-valve, while at the stations H and H' the regulators are connected with time-valves K K', applied to the 15 tube D. When the doors I I' are thrown open, the time-regulators J J' are thereby set and the valves K K' are thrown open by the quick movements of the pistons of said regulators in one direction and controlled in closing by 20 the comparatively slow movement thereof in the opposite direction, the doors themselves being quickly closed. At the station H² the door I² is regulated in its closing action by the time-regulator J². At the station H² the delivery end of the tube D is supplied with a 25 valve-casing L, the inner or upper end of which is joined by a branch pipe L' to the pipe G, adjacent to its despatching end near the cashier's station, which is denoted by M 30 and within reach of which are located the charging or despatching ends of the distributing-tubes. The tube G is supplied with a valve-casing (indicated by the letter L²) which is similar to the valve-casing and contained 35 valve at station H². A detail of this last-named valve-casing appears in Fig. 3, showing it equipped with a valve L³, which seats inwardly or toward the main part of the tube G or away from its discharge end, and opens 40 outwardly or toward such discharge end. An exhaust or suction pipe N connects the upper part of said casing with the low-pressure pipe C. It is evident that when a carrier arrives at either of the stations M and H² it will shoot 45 past the branch pipe of the valve-casing thereat and be delivered to the attendant.

A detail of the casing D³ (casings E³ F³ being similar thereto) appears in Fig. 4, showing the lower section of the tube D extending 50 into the casing and provided with slots b, affording air-passages, and the extreme upper end of said tube-section left imperforate and affording a valve-seat b' for a combined valve and door b², which seats outwardly or toward 55 the despatching end of the tube D and opens inwardly or toward the main or conveying part of said tube. The detail further shows the lower end of the upper tube-section extending into the casing and slotted and expanded to form a guide for conducting the carrier 60 smoothly past the junction with the pipe D⁴. It will be understood that the pipe D⁶ being under suction a carrier inserted through the door D' will be carried upward by atmos-

pheric pressure with enough force to acquire 65 sufficient momentum to cause it to pass the valve b² and enter the path of a blast from the pipe D⁴.

A detail of the door I, regulator J, and valve K is shown in Fig. 2. All the regulators 70 employed are similar to the regulator there shown.

P represents a piston supplied with perforations c and moving within a closed casing. The piston is rigid with a piston-rod c', one 75 end of which is connected by a link c² with the valve K and the opposite end of which is connected by a link c³ with the door I. The link c³ is provided with a slot c⁴, engaging a pin c⁵ on-said door. Between the piston and 80 one end of the casing is confined a spring c⁶, and on the opposite side of the piston is a movable washer or valve-disk c⁷. The casing contains oil, air, or other fluid, which when 85 the piston is moved against its spring passes readily through the perforations c, but in the return movement is caused to pass through a channel c⁸, the size of which is regulated by a set-screw c⁹. The door I is pivoted at d and with a spring d' for closing it quickly. The 90 valve K is pivoted at e, and adjacent to said valve is an outwardly-seating check-valve e', the purpose of which is to prevent escape of air from the tube D under any possible working conditions while the admission-valve D⁶ is 95 open.

The construction at station H' is exactly like that described at station H.

The construction at station H² has been partially described. The combined door and valve 100 I² is pivoted at f and when opened acts through an arm f' and link f² on the piston-rod c' of the regulator J², (similar to regulator J.)

At station M the doors D' E' F' act also as 105 time-valves, being connected to the regulators in the same manner as has been described with reference to door I². Here, however, the piston-rods c' of the regulators are connected at their ends opposite the doors with the slide or gate valves D⁶ E⁶ F⁶. A detail of one of those 110 valves is shown in Figs. 5 and 6, showing a guide g for the valve to move in as it is withdrawn. The time-regulators are shown attached to the several adjacent tubes by bracket-arms Q. 115

In Fig. 1 a pipe C' is shown in communication with the low-pressure pipe C. It is supplied with a diaphragm C², which connects by link-and-lever mechanism or by any other suitable device with the governor of the engine or motor which runs the fan. As the pressure is lessened in the pipe C, or at the low-pressure side of the fan, the action of this mechanism is to so affect the governor as to cause the motor to slacken its speed; but when air is admitted to the said low-pressure side, as will occur when one of the despatching-doors is opened, the speed of the motor and 120 125 130 135 140 145 150

the fan will be increased, so as to give an ample supply of air to transmit the carrier to its destination. An inwardly-opening valve C³ is provided, which opens to admit air to the 5 pipe C in case the motor slackens its speed too much. A relief-valve for the high-pressure pipe C may be provided, none being shown.

It is to be noted that the same general principle or mode of operation obtains in the 10 operation of the speed-regulating device for the air-compressor when the same is operating in connection with the distributing-tube as when operating in connection with the collecting-tube. This will be made plain from consideration of the fact that the collecting-tube G will be normally closed to the admission of air, and when a carrier is sent through the same—as, for instance, by being inserted through the door I²—air will flow through said tube 15 only during the time that the door I² remains open and the said carrier is passing through said tube. Access of air through the delivery end of the tube G to the exhaust-pipe N will be prevented by the valve L³, so that the speed-regulator will act to increase the speed of the 20 compressor only during the time that the air is flowing through said collecting-tube. Similarly, with respect to the parts of the distributing-tube D, adjacent to its despatching end, 25 air will be drawn through the part of said tube between the despatching-door D' and the valve-casing D³ when said door is open, and any flow of air to the exhaust-tube E⁵ except through said door is prevented by the valve b² in the casing D³. In the case of a 30 distributing-tube, however, an additional and further effect is produced for the reason that the opening of a door, as D', not only admits air to the low-pressure side of the compressor 35 for the purpose of carrying the carrier from the admission-door to the valve-casing D³, but said door remains open long enough to convey the carrier to its destination, it being obvious that during the passage of the carrier through 40 the main part of the tube D air entering the despatching-door D' passes through the exhaust-pipe D⁵ to the exhaust side of the compressor and then passes from the compressor 45 through the air-supply pipe to the tube D. In other words, the admission-door D' controls not only the supply of air to the low-pressure side of the compressor, but also the air supplied from the same to the air-supply pipe D⁴, because unless the air be admitted to 50 the low-pressure side of the compressor through the door D' there is no source of air-supply for sending the carrier through the distributing-tube. It follows from the above 55 that in the case of both of the collecting-pipe and the distributing-pipe the speed-regulator applied to the low-pressure side of the compressor has the effect of increasing the speed of the compressor to give the required supply of air during the time of the passage of

the carrier through the conveying-tube, while 65 insuring a cessation of the flow of air through the conveying-tube and a minimum speed in the motor which drives the compressor at times when there is no carrier being transmitted.

The operation has been indicated in the above description. It may be summarized thus: Under the action of the fan air is transferred from the pipe C and accumulates in the pipe B. The charging ends of the tubes 70 D, E, and F are normally at low pressure owing to their communication through the pipes D⁶, E⁶, F⁶ with the low-pressure pipe C. When therefore the door F', for example, is opened, and simultaneously therewith the valve F⁶, and the carrier is inserted into the charging end of the tube, the carrier is forced inward by atmospheric pressure, gaining sufficient momentum to carry it past the valve at F⁶ and into the path of the high-pressure 80 current from the pipe F⁴, by which it is carried to station H. Similarly, carriers inserted at E' and D' are carried to stations H' and H², respectively. At the latter station the discharge is past the valve at L, as described. 85 As stated, the collecting-tube G is normally at low pressure through connection with the pipe C. When, therefore, a carrier is introduced through either of the doors I, I', and I², it is carried by atmospheric pressure to station M, 90 discharging through the valve L³. A valve K or K' or door I², as the case may be, is held open long enough for the carrier to reach its destination. With the arrangement of 95 tubes shown it is obvious that the portion of the distributing-tube D outlying beyond the station H is utilized for supplying air to the collecting-tube G during the time that a carrier inserted at station H is passed to station M. In performing this function said portion 100 of the pipe D acts virtually as an inward or backward extension of the collecting-tube.

The feature of introducing or feeding carriers into a tube by means giving to the carriers an initial impulse sufficient to carry them 105 past a valve and into the course of a compressed-air current by which they are conveyed to their destination is herein broadly claimed. The drawings illustrate the despatching ends of the tubes as arranged vertically and opening downward and the valve above the despatching-door as a downwardly-seating one; but the said despatching ends of the tubes as well as the said valve may be arranged horizontally or in any other desired 110 position.

An important feature of novelty in the apparatus embodying my invention is embraced in the employment of means for controlling the period of closing of the admission-doors 115 and air-valves operating independently of the air-pressure or means for producing air-pressure in the apparatus, such independent time-

controlling means having the advantage that by its use a number of carriers may be despatched through the tubes one after another at close intervals and without awaiting the discharge of one carrier from the tube before another is inserted, it being obvious that if the despatching-door in either the distributing or collecting tube be partially closed it may be reopened at any point in its closing movement and another carrier inserted after the one previously inserted, the air pressure or suction, as the case may be, continuing until the carrier last inserted has reached its destination.

15 An important advantage is gained in a pneumatic conveyer of the kind herein illustrated by the employment of pressure-actuated controlling means for governing the action of the motor which drives the air-compressor. This 20 will be understood by consideration of the fact that in the apparatus described when no carriers are being sent in either direction through the distributing or collecting tube access of air to said tubes is prevented by the 25 valves applied to said tubes, so that the air-compressor and motor driving it, while continued in operation, will be doing little or no work and will require the use of power only sufficient to keep them in motion. As soon, 30 however, as the air is admitted at the suction side of the compressor additional power is immediately applied to the compressor, and the speed of the same is increased in accordance with the work to be done or, in other words, 35 in accordance with the number of carriers being sent at any one time through the system and the distance which they travel. It follows that a minimum of power is expended when no carriers are being sent, that when 40 one carrier is sent through the system only enough power is required to drive that carrier, and the expenditure of power will cease as soon as the carrier reaches its destination, and that when a large number of carriers 45 are being transmitted simultaneously through the different parts of the system, then the amount of power used will correspond exactly with the requirements of the carriers to be transmitted. It follows that in the use of electricity as a motive power the quantity of current used will correspond exactly with the number of carriers transmitted and the distances through which they travel, and similarly in the use of a steam-engine, gas-engine, 50 or any other source of power the power expended will only be that required for transmitting the carriers, and substantially no power will be expended in moving air-currents when no carriers are in transit.

55 Changes in details of construction may be made without departure from my invention. Hence no limitation is intended by the particular description given, except as may appear from the appended claims. Any means for

producing movement of air through the tubes 65 may be employed in connection with the time-regulator for controlling the periods of closing of the admission-valves, whether said valves be to admit compressed air or air of atmospheric pressure to the tubes.

70 I claim as my invention—

1. In a pneumatic conveyer, the combination of a distributing-tube, a collecting-tube connected with the distributing-tube near the delivery end of the same, a despatching-door for 75 said collecting-tube, an air-admission valve on the distributing-tube connected with said door, means for controlling the period of closing the said air-admission valve, an inwardly-seating valve at the delivery end of said distributing-tubes and means for applying suction to said 80 collecting-tube near its delivery end.

2. In a pneumatic conveyer, the combination of a distributing-tube, a collecting-tube provided with a despatching-station, means for applying pressure to said distributing-tube, and suction to said collecting-tube, valves controlling the flow of air into and through said tubes, a pipe connecting said distributing-tube near its delivery end with said collecting-tube, and an inwardly-seating valve in the delivery end 90 of said last-named distributing-tube beyond or outside of said connecting-pipe.

3. In a pneumatic carrying system, the combination of a plenum side, a vacuum side, 95 mechanism for maintaining the pressure on both sides, and an automatic governing device operatively connected with one side of said system and operated by variations in pressure on the side with which it is connected and arranged to control said pressure-supplying mechanism whereby the operation of the latter is accelerated whenever the pressure which operates the governing device falls below a 100 determined point.

105 4. In a pneumatic carrying system, the combination of a plenum side, a vacuum side, a blower having its inlet connected with the vacuum side, and its outlet discharging into the plenum side, a motor actuating said blower, a 110 governor controlling said motor, and a pressure-actuated governor connected with one side of the system and adapted to act upon the motor-controlling governor.

115 5. In a pneumatic conveyer system, the combination of a distributing-tube, a collecting-tube, a blower having its outlet and inlet sides respectively connected with said distributing and collecting tubes, a connecting-passage between said collecting and distributing tubes at 120 a point remote from the blower, and means for passing carriers through either side of said system.

125 6. In a pneumatic conveyer system, the combination of a distributing-tube, a collecting-tube, a blower having its outlet and inlet sides respectively connected with said distributing and collecting tubes, a connecting-passage be-

tween said collecting and distributing tubes at a point remote from the blower, and means for passing carriers through either side of said system, a motor driving said blower and an automatic governor controlling said motor and operatively connected with one side of said system, whereby variations in pressure operate to control the speed of the motor.

In testimony that I claim the foregoing as my invention I affix my signature, in presence ¹⁰ of two witnesses, this 2d day of June, A. D. 1900.
